UNITED STATES PATENT OFFICE.

BENJAMIN SCOTT BENSON, OF BALTIMORE, MARYLAND.

SURFACE-CONDENSER.

SPECIFICATION forming part of Letters Patent No. 328,752, dated October 20, 1885.

Application filed February 17, 1885. Serial No. 156,146. (No model.)

To all whom it may concern:

Be it known that I, BENJAMIN SCOTT BENSON, a citizen of the United States, residing at Baltimore city, State of Maryland, have invented certain new and useful Improvements 5 in Surface-Condensers, of which the following is a description.

Figure 1 is a vertical section of the condenser-case, with a part of the cells also shown in section. Fig. 2 is a horizontal section through the line $\alpha\alpha$ of Fig. 1.

My invention relates to surface-condensers; and its object is to provide means for condensing steam, to save the water where the latter is scarce, and render it in a pure condition to supply traction-engines, railroad-locomotives, &c., and especially for supplying traction-engines designed to be used on the Western prairies for plowing the ground; and it consists in the peculiar construction and arrangement of parts of an atmospheric condenser in which steam passes through a set of cells in one direction, and is condensed by a current of cold air blown forcibly through an alternate or intermediate set of cells separated from the steam-cells only by thin metal partitions, as will be hereinafter fully described.

In the drawings, A represents the outer casing of the condenser, which is of square shape, but may be of any other desired form. Vertically within this case are arranged the steam-cells $a a a$, &c., and alternating air-cells $b b b$, &c., which are formed by parallel plates of very thin brass placed almost in contact with each other, but spaced a short distance by having pits indented in one side and projecting on the other, which projections prevent one plate from lying flat against the other, and separate the plates a short distance, to form very flat chambers with very little capacity but an immense amount of surface. By this construction I can get a sufficient surface-exposure within a limited space to practically meet the requirement of condensing steam by air. The cells $a a a$ alternate with but are separate from $b b b$, and each cell is soldered up tight. The steam-cells $a a a$ open at the top into a steam-chest, B, in the top of the outer case, to which exhaust-steam is fed by the pipe B', and the steam-cells $a a a$ at their

lower ends have each a pendent drip-tube, c, that conveys the condensed water through a cover, C, into a subjacent water-receiver, D, from which water is drawn off through the pipe D', to be fed through the pump to the engine again. The drip-tubes c are seated at their lower ends in the water, but not so deep but what any air may blow out that happens to get in the steam-cells. The water-receiver 60 D has a series of cross-partitions, d, in the same, which do not quite extend up to the top of the pan, and over which the water can flow when the pan is nearly full, but which prevents the bulk of the water from swashing from end to end of the pan and overflowing when the engine moves up or down grade or deviates from a horizontal plane.

Between the horizontal cover C of the water-receptacle and the lower ends of the cells is left a cold-air space, into which cold air is forced through a pipe, E, from a blower, F. With this air-space the air-cells $b b b$ communicate directly, the lower ends of said air-spaces being entirely open, while the upper ends of the air-spaces communicate, through a series of short horizontal side tubes, e e, on each side, with gathering-tubes G G on the outside of the case, which carry the hot air to a common outlet, G'.

In the operation of my condenser it will be seen that the steam and air pass in opposite directions, the cold air entering at the end where the condensed steam escapes, and the warm air leaving at the end where the hot steam enters, thus making the condensation of steam gradual and uniform. This is a matter of considerable importance with this particular condenser, (made of thin plates,) inasmuch as it prevents that sudden condensation and partial vacuum, which would cause the collapse and rupture of the cells, and which would not be quickly enough relieved by the vacuum-valve, hereinafter referred to.

In the top of the steam-chest is an outwardly-opening safety-valve, f, set to open at a pressure which is lighter than that sufficient to rupture the thin cells, and in said steam-chest is also an inwardly-opening vacuum-valve, g, that prevents the collapse of the steam-cells when they become cold from disuse, or from a partial vacuum while working.

In some forms of my invention I may use pipes for steam-cells and blow cold air around them; but I prefer the flat cells, on account of their greater surface and less weight. Instead 5 of a blower for forcing the air through a condenser, the draft of the smoke-stack may be utilized for this purpose.

I may also arrange the steam and air cells horizontally instead of vertically.

10 Having thus described my invention, what I claim as new is—

1. The blower, cold-air chamber, air-cells, warm-air pipes, and their connections, in combination with steam-chamber, steam cells or condensers, and hot-water reservoir, and drip-pipes, substantially as described.

15 2. The combination of steam-cells *a* and air-cells *b*, the case *A*, having steam-chest at the

top communicating with the steam-cells, and hot-air pipes communicating with the air-pipes *b*, and gathering-pipes on the outside of the case, and a hot-water receptacle in the bottom of the case connected by pipes with the steam-cells, and an air-space between the water-receptacle and the air-cells, communicating with the lower ends of the latter, substantially as shown and described.

20 3. The combination, with the steam-cells of an air-condenser constructed and operating substantially as shown, of a vacuum and safety 30 valve, substantially as and for the purpose described.

BENJAMIN SCOTT BENSON.
